US00D835282S

(12) **United States Design Patent** (10) Patent No.: **US D835,282 S**
(45) Date of Patent: ** Dec. 4, 2018

(54) **MEDICAL MONITORING DEVICE**

(71) Applicant: **MASIMO CORPORATION**, Irvine, CA (US)

(72) Inventors: **Nicholas Evan Barker**, Laguna Beach, CA (US); **Ammar Al-Ali**, San Juan Capistrano, CA (US); **Chad A. DeJong**, Los Angeles, CA (US); **Sujin Hwang**, Irvine, CA (US); **Massi Joe E. Kiani**, Laguna Niguel, CA (US); **Bilal Muhsin**, San Clemente, CA (US)

(73) Assignee: **Masimo Corporation**, Irvine, CA (US)

(**) Term: **15 Years**

(21) Appl. No.: **29/602,282**

(22) Filed: **Apr. 28, 2017**

(51) LOC (11) Cl. **24-01**

(52) U.S. Cl.

USPC **D24/186**

(58) **Field of Classification Search**

(57) **CLAIM**

The ornamental design for a medical monitoring device, as shown and described.

DESCRIPTION

FIG. 1 is a front, side, and bottom perspective view of a medical monitoring device embodying our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

Broken lines are used to illustrate portions of the medical monitoring device that form no part of the claimed design.

1 Claim, 7 Drawing Sheets
